2,157,504.

PARACHUTE HARNESS

Floyd Smith, Buffalo, N. Y., assignor to Irving
Air Chute Co. Inc., Buffalo, N. Y., a corpora-
tion

Original application March 31, 1937, Serial No.
134,109. Divided and this application January
7, 1938, Serial No. 183,923

4 Claims. (Cl. 244—151)

This invention relates to improvements in para-
chute harnesses.

The present application is a division of my co-
pending application, Ser. No. 134,109, filed March
5 31, 1937, now Patent 2,130,569.

Other objects and advantages of the invention
will be apparent during the course of the fol-
lowing detailed description.

In the accompanying drawing forming a part
10 of this specification, and wherein similar refer-
ence characters designate corresponding parts
throughout the several views,

Figure 1 shows the improved parachute appa-
ratus including an improved harness and soft
15 pack in releasably coupled relation with each
other upon a wearer.

Figure 1^a is a perspective view of the improved
soft pack, with part of the pocket cut away to
show the rip cord construction.

Figure 1^b is an enlarged sectional view taken
20 through a portion of the rip cord and handle
construction.

Figure 2 is a perspective view of the improved
harness.

Figure 3 is a fragmentary sectional view show-
25 ing the complementary coupling parts of the pack
and harness and the relative construction and
assemblage thereof.

In the drawing, wherein similar reference char-
30 acters designate corresponding parts throughout
the several views, the letter A may generally des-
ignate a form of harness with which the improved
soft pack B may be used.

The improved harness A is of the multiple re-
lease type, although some characteristics thereon
35 may be adaptable for use with the single point
quick release type such as shown in U. S. Pat-
ent #1,899,656. In the main it comprises a body
supporting sling 20, consisting of a double thick-
40 ness of webbing. These thicknesses are stitched
together and provide a seat portion 23 upon
which the wearer sits during a parachute des-
cent. Side riser portions 24 and 25 extend from
45 the seat portion and comprise part of the sling.
They continue upwardly to provide shoulder
straps 26 and 27, and the latter extend down-
wardly to provide crossed back straps 28 and 29.
The double thickness of webbing of the support-
50 ing sling ends at the crossing point of the back
straps 28 and 29, where a slip connection 30 is
provided. The back straps 28 and 29 from the
crossing point 30 extend in relative divergence
55 downward and are permanently stitched at 32
and 33 to the riser webs 25 and 24 at a location
normally below the peak of the hips of the wearer.

In each of the back straps 28 and 29 adjacent to
the connections 32 and 33 there is provided an
adjustment for the back strap. This adjustment
consists of providing an adapter 35 in each of
the back straps, secured to a small looped portion
5 of the back strap, which is the portion directly
connected with the sling. The ends 37 of the
back straps 28 and 29 are secured through these
adapters in an adjustable relation (see Figure 2
of the drawing).

The back straps 28 and 29 extend beyond their
connecting points 32 and 33 on the riser webs of
the supporting sling, in a forward direction, and
are then turned back and stitched at 40 on the
ends of the seat strap of the sling at a location
15 below the points 32 and 33. This provides strap
loops 42 and 43 on the supporting sling at each
riser web 24 and 25, on which leg strap coupling
parts 46 are secured. They may be either cou-
pling rings or snap fasteners, as desired. The
20 hip strap 50 is extended horizontally so as to be
at a location appreciably below the small of the
back of the wearer in order to prevent the para-
chutist from falling rearwardly through the har-
ness and retain the parachutist in the harness
25 without liability of injury at the time of shock
opening of the parachute canopy.

The harness additionally includes leg straps 48
and 49 secured to the intermediate portion of
the seat strap 23 and having coupling parts 50
30 thereon for complementary association with the
coupling parts 46 above mentioned. These leg
straps each having an adjustment therein, of well
known construction.

It will be noted from Figure 2 of the drawing
35 that the inner layer or thickness of the support-
ing sling terminates at the shoulder straps and
that the back straps 28 and 29 from the shoul-
der stitching point 60, shown in Figure 2, com-
prise a layer which is extended forwardly at each
40 of the riser webs, to provide the breast straps
63 and 64 which relatively converge towards each
other and are permanently connected at locations
70 on the riser webs above the stitch locations
32 and 33 of the back straps. On these loose
45 breast straps 63 and 64 are disposed comple-
mentary coupling parts 73.

Pack coupling rings 75 and 76 are permanently
secured in a definitely fixed relation upon the
riser webs 24 and 25 respectively, at a location
50 immediately above the breast strap connections
70. These couplings are preferably rings, and
they outstand normal to the plane of the riser
webs on which they are located; the connection
being such that at all times they will outstand
55

in this relation to facilitate connection of the pack coupling parts thereto. Stiffening loops 78 are secured to the riser webs in a stitched relation below the coupling parts 75 in order to stiffen the riser webs at this location and thus facilitate the application of the coupling parts of the pack to the coupling parts 75. These straps 78 also form loops thru which the coupling parts 75 are connected, as shown in Figure 3.

10 Referring to the soft pack B, the same includes a flexible sheet-like container C which houses a parachute canopy. As set forth in my above identified parent application the canopy is provided with the usual suspension straps having 15 the couplings 104 attached thereto; the suspension straps being designated at 102 in Figure 3 of the drawing. These couplings are preferably of the snap variety and are adapted for connection with the complementary coupling parts 75 and 20 76 in order to connect the pack B to the harness.

25 The container of the pack B is provided with a body portion having flaps 113 which open to permit exodus of the parachute canopy, and the pack container is additionally provided with a handle 140, shown in Figure 1.

30 As is shown in Figure 3 of the drawing each of the snap fastener couplings 104 is provided with an aperture stud 130^a thereon. The container is provided with eyelets 131 thru which 35 these studs 130^a extend. Each suspension web 102 of the canopy is provided with a flexible wire pin 138 adapted to extend thru the aperture of the stud 130^a when the latter is projected into the pack. This holds the coupling 104 externally 40 in a fixed relation upon the container, when the latter is packed, so that when a wearer desires to apply the pack upon the harness it is not necessary to fumble with the coupling parts. Reversal of the coupling parts on the harness and pack may be made if so desired, without departing from the spirit of this invention or the scope of the claims.

45 As shown in Figure 1^a of the drawing a wire rip cord 150 is provided, having the usual retaining wire pins thereon for extension thru the apertures of the studs 145, in order to hold the grommets on the studs and the container closed with the canopy packed therein. The end flap 113 is provided with a pocket 153 adapted, as shown in Figure 1^a of the drawing, to house a rip cord handle 154. The latter is provided with a base bar 50 155^a having a central opening 155 through which the rip cord 150 is slidable. The rip cord 150 at one end is provided with a stud 156 to prevent 55 displacement of the rip cord from the handle 154, and at the opposite side of the base bar 155^a the rip cord 150 is prevented from detachment from the handle by means of the retaining pins above described. The reason for slidably extending the rip cord 150 on the base bar 155^a is to prevent premature release opening of the 60 parachute pack due to eccentricities in packing or variances in usual packing dimensions. As shown in Figure 1^a, when the pack is in closed 65 condition the handle 150 is located in the pocket 153 and with the retaining pins of the rip cord in position in the apertures of the studs the retaining lug 156 on the end of the rip cord 150

is still spaced an inch or more from the base bar 155^a. This distance enables a length play of the rip cord 150 sufficient to take care of all discrepancies during packing. Thus there will be no liability of premature release or opening of the pack, due to improper length of the rip cord or improper positioning of the handle in its pocket.

10 Various changes in the shape, size, and arrangement of parts may be made to the form of invention herein shown and described, without departing from the spirit of the invention or the scope of the claims.

I claim:

1. Parachute harness comprising a U-shaped 15 supporting sling including a seat portion and riser webs, back strap means connected with the sling, breast straps connected with the riser portions adjacent the shoulder of a wearer and extending freely forwardly in looped relation and each connected with the adjacent side riser portions of the sling adjacent to the normal waist of a wearer, and definitely fixed and located coupling members connected with each of the riser portions of the harness at a location above 20 where the breast straps are connected with said riser portions.

2. Parachute harness comprising a U-shaped supporting sling including a seat portion and riser webs, back strap means connected with the 30 sling, breast straps connected with the riser portions adjacent the shoulder of a wearer and extending freely forwardly in looped relation and each connected with the adjacent side riser portions of the sling adjacent to the normal waist 35 of a wearer, definitely fixed and located coupling members connected with each of the riser portions of the harness at a location above where the breast straps are connected with said riser portions, and means stiffening the riser portions 40 at a location below said coupling members.

3. In parachute harness the combination of a 45 suspension sling including a seat and side riser portions, other body attaching straps connected with said sling, coupling members connected in definitely fixed outstanding relation upon the riser portions at the front of the wearer, and means stiffening the riser portions of the harness immediately below said coupling members in order to facilitate the attachment of coupling 50 members of a pack with the coupling members of the harness.

4. Parachute harness comprising a U-shaped 55 supporting sling including a seat portion and riser webs, back strap means connected with the sling, breast straps connected with the riser portions adjacent the shoulder of a wearer and extending freely forwardly in looped relation and each connected with the adjacent side riser portions of the sling adjacent to the normal waist 60 of a wearer, and definitely fixed and located coupling members connected with each of the riser portions of the harness at a location above where the breast straps are connected with said riser portions and in transverse outstanding relation 65 with respect to the portions of the harness on which they are located.

FLOYD SMITH.
